US0D1065077S

(12) **United States Design Patent** (10) **Patent No.:** **US D1,065,077 S**
(45) **Date of Patent:** **** Mar. 4, 2025**

(54) **FOLDING WIRELESS CHARGER**

(71) Applicant: **Huizhang Xian**, Wanyuan (CN)

(72) Inventor: **Huizhang Xian**, Wanyuan (CN)

(**) Term: **15 Years**

(21) Appl. No.: **29/880,016**

(22) Filed: **Jul. 17, 2023**

(30) **Foreign Application Priority Data**

Mar. 9, 2023 (CN) 202330103141.6

(51) **LOC (15) Cl.** **13-02**

(57) **CLAIM**

The ornamental design for a folding wireless charger, as shown and described.

DESCRIPTION

FIG. 1 is a front perspective view of a folding wireless charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the folding wireless charger shown in a folded configuration.

The broken lines in the drawings illustrate the portions of the folding wireless charger, that form no part of the claimed design.

1 Claim, 9 Drawing Sheets
